DESIGN FOR AN AUTOMOTIVE DELIVERY VEHICLE

William S. Tandler and Ferdinand A. de Weiss,
New York, N. Y., assignors to Industrial Scientific
Company, New York, N. Y.

Application October 13, 1945, Serial No. 122,810

Term of patent 14 years

(CL. D14—3)

To all whom it may concern:

Be it known that we, William S. Tandler, and Ferdinand A. de Weiss, citizens of the United States of America and Austria-Hungary, respectively, residing at New York, in the county of New York and State of New York, have invented a new, original, and ornamental Design for an Automotive Delivery Vehicle, of which the following is a specification, reference being had to the accompanying drawings, forming part thereof.

In the drawings,

Fig. 1 is a top plan view of an automotive delivery vehicle showing our new design;

Fig. 2 is a side elevational view;

Fig. 3 is a front elevational view;

Fig. 4 is a side perspective view; and

Fig. 5 is a rear perspective view thereof.

We claim:

The ornamental design for an automotive delivery vehicle, as shown.

WILLIAM S. TANDLER.
FERDINAND A. DE WEISS.
